(57) **CLAIM**

The ornamental design for storage battery for lighting system, as shown and described.

DESCRIPTION

FIG. 1 is a top perspective view of the storage battery for lighting system;

FIG. 2 is a top view of the storage battery for lighting system;
FIG. 3 is a front view of the storage battery for lighting system;

FIG. 4 is a left side view of the storage battery for lighting system;

FIG. 5 is a right side view of the storage battery for lighting system;

FIG. 6 is a back view of the storage battery for lighting system; and,

FIG. 7 is a bottom view of the storage battery for lighting system.

The portions of the storage battery for lighting system shown in broken lines form no part of the claimed design.

The broken lines shown in the drawings are included for the purpose of illustrating environmental structure and form no part of the claimed design.
